UNITED STATES PATENT OFFICE

RAYMOND E. DODGE, OF NEW HAVEN, CONNECTICUT.

HOSE-SUPPORTER.

1,091,815.

Specification of Letters Patent. Patented Mar. 31, 1914.

Application filed August 9, 1913. Serial No. 783,881.

To all whom it may concern:

Be it known that I, RAYMOND E. DODGE, a citizen of the United States, residing at New Haven, in the county of New Haven 5 and State of Connecticut, have invented a new and useful Improvement in Hose-Supporters; and I do hereby declare the following, when taken in connection with the accompanying drawings and the characters of 10 reference marked thereon, to be a full, clear, and exact description of the same, and which said drawings constitute part of this application, and represent, in—

Figure 1 a front view of a hose supporter 15 constructed in accordance with my invention. Fig. 2 a side view of the same. Fig. 3 a plan view of the loop member detached. Fig. 4 a sectional view on the line *a*—*b* of Fig. 1. Fig. 5 a sectional view on the line 20 *c*—*d* of Fig. 3.

This invention relates to an improvement 25 in hose supporters, and particularly to hose supporters of the button-and-loop type, the object being to produce a supporter which will firmly hold the stocking and avoid as 30 far as possible the possibility of tearing; and the invention consists in the construction hereinafter described and particularly recited in the claim.

In carrying out my invention I employ a 35 double loop 2 having two elongated slots 3, 4, which are contracted at their inner ends 5, 6, in the usual manner of hose supporter loops. Preferably and as herein shown, the 40 central bar 7 which divides the loops is turned or swaged so as to form a narrow portion 8 for the purpose as will herein-after appear. This loop is connected with a transverse loop 9 by which the device is connected with the webbing 10. This connection may be of any approved construction. In connection with the double loops I employ two buttons 11 and 12 attached to a plate 13 which is connected to a short piece

of webbing also in the usual manner of hose supporters. These buttons 11 and 12 may be of any approved construction, preferably covered with rubber.

The device is applied to the stocking in the usual manner, that is, the buttons are 50 placed inside the stocking, and the loop set over the buttons and drawn upward so as to crowd the buttons into the contracted lower ends of the loops. The narrow portion of the central bar makes it easy to force the 55 fabric inward between the buttons so that sufficient material will be provided between the buttons to permit the lower ends of the loops to grip the fabric without unduly stretching it and allows the lower end or 60 wide portion of the central bar to grip the shanks of the buttons. Other advantages of bending or twisting the central bar are, that it assists in forming sufficient space for the clearance of the heads of the buttons 65 without widening the upper portion of the loop and permits the buttons to be arranged closely together.

I claim:

A hose supporter in combination with two 70 buttons arranged side by side, of a double loop having a central bar, a portion of the said central bar narrower than the space between the heads of said buttons, and the lower portion of the bar wider than the 75 space between the heads of the buttons whereby the upper narrow portion of the bar may be readily passed between the buttons and the wider lower portion engaged with the shanks thereof, substantially as described.

In testimony whereof, I have signed this specification in the presence of two subscribing witnesses.

RAYMOND E. DODGE.
